(57) **CLAIM**

The ornamental design for a round stove table, as shown and described.

DESCRIPTION

FIG. 1 is a perspective view of a round stove table showing our new design;

FIG. 2 is a rear view thereof;

FIG. 3 is a front view thereof;

FIG. 4 is a left side view thereof, a right side view being a mirror image of the left side view;

FIG. 5 is a top view thereof;

FIG. 6 is a bottom view thereof; and,

FIG. 7 is a partially enlarged view showing the area "7" in FIG. 1.

The dot-dash broken lines indicating an enlargement portion of the design form no part of the claimed design.

1 Claim, 7 Drawing Sheets
